PACKING MEMBER FOR FRAGILE ARTICLES

Philip M. Williams, Oakland, Maine, assignor to
Keyes Fibre Company, Portland, Maine, a cor-
poration of Maine

Application September 12, 1952, Serial No. 21,432

Term of patent 14 years

(Cl. D58—13)

To all whom it may concern:

Be it known that I, Philip M. Williams, a citizen of the United States of America, residing at Oakland, county of Kennebec, State of Maine, have invented a new, original, and ornamental Design for a Packing Member for Fragile Articles, of which the following is a specification, reference being had to the accompanying drawing forming part thereof.

Fig. 1 is a plan view of a packing member for fragile articles showing my new design;

Fig. 2 is an end view thereof; and

Fig. 3 is a vertical sectional view thereof taken along the line 3—3 of Fig. 1.

I claim:

The ornamental design for a packing member for fragile articles, as shown.

PHILIP M. WILLIAMS.
